UNITED STATES PATENT OFFICE.

GEORGE H. BLAXTER, OF BEAVER, PENNSYLVANIA.

OVERLOAD CONTROL FOR METAL ROLLS.

1,040,863.

Specification of Letters Patent.

Patented Oct. 8, 1912.

Application filed January 22, 1912. Serial No. 672,620.

To all whom it may concern:

Be it known that I, GEORGE H. BLAXTER, a subject of the King of Great Britain, and a resident of Beaver, in the county of Beaver 5 and State of Pennsylvania, have invented a new and useful Improvement in Overload Control for Metal Rolls, of which the following is a specification.

This invention relates to means for controlling electric motor driven metal reducing rolls or other machines.

The object of the invention is to provide an arrangement whereby damage to the rolls or operating parts of the machine, or their 15 driving mechanism, is largely prevented when the work sticks in the rolls or clogs the machine, or on account of excessive or dangerous overload from any other cause.

The invention comprises the construction 20 and arrangement of parts hereinafter described and claimed.

In the accompanying drawing Figure 1 is a view partly diagrammatic of the arrangement of apparatus, the switch being shown 25 in front elevation; Fig. 2 is a side view of the circuit breaker; and Fig. 3 is a cross section on the line 3—3, Fig. 2.

The present invention may be used for controlling the drive of any machine, the 30 duty of which renders it peculiarly liable to excessive or dangerous overload. In the drawings however, I have shown the invention as applied for the control of the rolls of a metal reducing rolling mill. The rolls 35 may be of any character, but are represented by rolls 2 and 3 such as are used in rolling plates or bars. These rolls are mounted in the usual housings and bearings, and are driven from a suitable motor, that illustrated being an electric motor 5 suitably 40 connected by a shaft and gearing to the necks of the rolls. In conjunction with such rolls it is customary to use a fly wheel 6 usually placed in the connection between the 45 motor and the rolls, being shown as mounted upon shaft 7, which is in two sections 7^a, 7^b, and forms part of such connection. 8 indicates the mains of the circuit for supplying current to motor 5.

On the occurrence of excessive overloads 50 with electric motor driven rolls it has been proposed to break the motor supply circuit. This, however, leaves the fly wheel connected to the rolls with the result that the fly wheel 55 produces more or less mischief or damage.

With my new arrangement I break the

connection between the fly wheel and rolls, or broadly speaking, break the connection between the rolls and both the fly wheel and the motor. This may be variously accomplished, but as shown there is in the connection between the motor 5 and the rolls and particularly between the fly wheel and rolls, a magnetic coupling 10 of suitable form. Such magnetic couplings or friction clutches 60 are well known, the same comprising an iron disk secured to one of the shaft sections 7^a, and a corresponding disk secured to the other shaft member 7^b, one or both of which are provided with windings 11 supplied by 65 slip rings 12 in a branch or shunt circuit 13 from the main supply circuit 8. It is perfectly obvious that as long as current is supplied to the windings of the coupling the two members thereof are attracted and, with 70 the shaft sections, rotate in unison, but when the current to the winding or windings is interrupted the coupling becomes inactive and the shaft sections are free from each other.

In the circuit of the magnetic coupling is located a circuit breaker of some convenient form arranged and designed so as to open 75 said branch circuit 13 in case of an overload on motor 5. Such overload circuit breakers 80 are very well known. As shown, it comprises an actuating winding or solenoid 16 in the main supply circuit 8 to motor 5 and an armature or core 17 therefor controlling switch 18 in the branch circuit 13. The 85 winding and armature of the circuit breaker are so proportioned that upon normal current to motor 5 the armature is not actuated, but upon the occurrence of abnormal current to motor 5, such as occurs upon excessive 90 overload, the armature or core is attracted to open switch 18, thereby interrupting the flow of current to the magnetic coupling and releasing the rolls from the 95 connection both of motor 5 and of fly wheel 100 6 by release of the shaft sections 7^a, 7^b from each other.

To prevent considerable flash and the danger of breaking down the insulation in the coils of the magnetic clutch I provide the 105 particular form of circuit breaker shown in detail in Figs. 2 and 3, in connection with which is used a suitable non-inductive resistance 15 in a branch or shunt circuit 19 across the clutch circuit 13. The wires of 110 this branch circuit 19 are led to contacts 20 on the back of the wall panel or plate 21, on

the forward face of which is pivotally mounted the switch or circuit breaker 18 referred to. To close the contacts 20 a bridge 22 is provided mounted on the end of a rod 23 projecting through the panel and loosely engaged by the switch 18. A compression spring 24 is placed between the headed end of rod 23 and the panel to constantly tend to close contacts 20. As shown the core or armature 17 is connected to a latch 25 which has a hooked end engaging a portion of the switch 18 to hold the same closed. Upon rise in the current due to abnormal conditions the core 17 lifts the latch 25 releasing the switch 18 to the action of spring 24 which throws the switch open and at the same time closes the contacts 20 by means of the bridge 22. A closed circuit is now established through the clutch coils and slip rings and the non-inductive resistance 15. The latter dissipates the shunt discharge and obviates the possibility of sudden rise of potential which might injure the clutch coils. When the switch 18 is again closed it engages rod 23, compresses spring 24 and opens contacts 20, the latch 25 again holding it in closed position.

The arrangement described is a very simple one for protecting the rolls and the work therein from the evil effects of an excessive overload, or from the effects of the fly wheel in case the circuit to the motor is broken. The particular arrangement shown in the drawings breaks the connection to the roll between the fly wheel and the rolls. In case the fly wheel is on the opposite side of the rolls from the motor, a pair of magnetic couplings are necessary, one to disconnect the motor from the rolls and the other to disconnect the fly wheel from the rolls.

Various other arrangements of automatic means for effecting the same results upon the occurrence of excessive or dangerous overload will readily suggest themselves.

45 What I claim is:

1. The combination of the operating parts of a machine, a motor for driving the same, a fly wheel connected to said machine, connections from said motor and fly wheel to said machine, and means controlled by the power supply of said motor and arranged to disconnect the fly wheel and motor from said machine on abnormal fluctuation in the power supply.

55 2. The combination with the operating parts of a machine, of a motor for driving the same, a fly wheel connected to the machine, and means controlling the connections between the fly wheel and the machine and arranged to disconnect the fly wheel from the machine on variation in the power supply to the motor.

3. The combination with the operating parts of a machine, of a motor for driving the same, a fly wheel connected to said ma-

chine, a disconnectible coupling between the fly wheel and the machine, and means controlled by the power supply of said motor and arranged to disconnect said coupling on the occurrence of overload.

4. The combination with the operating parts of a machine, of a motor for driving the same, a fly wheel driven by said motor, a releasable connection between said motor and the machine, and means controlled by the power supply of said motor for releasing the machine from the motor and fly wheel.

5. The combination with the operating parts of a machine, of a motor for driving the same, a fly wheel connected to said machine, connections from said motor and fly wheel to said machine, and means controlling said connections and arranged to disconnect the fly wheel and motor from said machine on variation in the power supply to the motor.

6. The combination with the operating parts of a machine, of an electric motor for driving the same, a fly wheel connected to said machine, connections from said motor and fly wheel to said machine, and electrically controlled means arranged to disconnect the fly wheel and motor from said machine on occurrence of excessive or dangerous overload.

7. The combination with the operating parts of a machine, of an electric motor for driving the same, a fly wheel connected to said machine, connections from said motor and fly wheel to said machine, and a magnetic coupling in said connections arranged to disconnect the fly wheel and motor from the machine on an occurrence of excessive or dangerous overload.

8. The combination with the operating parts of a machine, of an electric motor for driving the same, a fly wheel connected to said machine, connections from said motor and fly wheel to said machine, a disconnectible coupling in said connections, an overload magnet in the motor circuit and connections whereby said magnet controls said coupling, said connections being arranged to disconnect the motor and fly wheel from said machine on occurrence of overload.

9. The combination with the operating parts of a machine, of an electric motor for actuating the same, a fly wheel connected to said machine, connections from said motor to said machine, a magnetic coupling in said connections, and an overload switch arranged in the circuit to the motor and controlling the circuit to said coupling.

10. The combination with the operating parts of a machine, of an electric motor for driving the same, connections between the said motor and machine including a fly wheel, a disconnectible clutch in said connections between the fly wheel and the ma-

chine, movable means controlling said clutch, and an overload magnet in the motor circuit arranged to control said movable means.

5 11. The combination with the operating parts of a machine, of an electric motor having connections for driving the same, a fly wheel, connections from said fly wheel to said machine, a magnetic clutch in said connections, the clutch coils being in shunt to

the motor circuit, a switch in the clutch circuit, and a magnet in the motor circuit for controlling said switch.

In testimony whereof, I have hereunto set my hand.

GEORGE H. BLAXTER.
